CIRCULAR KNITTING MACHINE AND METHOD OF OPERATING SAME

Albert E. Page, Brooklyn, and Harry Swinglehurst, Jr., Floral Park, N. Y., assignors to Scott & Williams, Incorporated, New York, N. Y., a corporation of Massachusetts

Application April 1, 1936, Serial No. 72,188

11 Claims. (Cl. 66—12)

This invention relates to a circular knitting machine and method of operating same, and more particularly to yarn feeding means when an elastic yarn is to be laid in plain fabric. One object of the invention is to provide a simplified and improved mechanism for tying an elastic yarn in the top of an anklet. The invention contemplates novel manipulations of the needles and elastic yarn finger to incorporate the elastic yarn in the fabric in an efficient manner.

In the drawings,

Fig. 1 is a developed view, in elevation and plan, of pertinent parts of the cam cylinder and needles of a circular knitting machine embodying our invention, showing the novel manipulation of the needles and their relation to the elastic yarn finger, the arrow indicating the direction of movement of the needles;

Fig. 2 is a schematic view of the special needle cams used in connection with the insertion of the elastic yarn and showing how these cams affect the elevations of the different needles;

Fig. 3 is a plan view of the machine of Fig. 1, taken below the latch ring on the line 3—3 of Fig. 6, showing so much of the head of the machine as is necessary to illustrate the special needle butt cams and controls;

Fig. 4 is a view in elevation of so much of the left side of the machine as is necessary to illustrate the controls for the elastic yarn finger and one of the needle butt cam slides;

Fig. 5 is a plan view of sufficient of the head of the machine, taken at a level above the latch ring, to show the controls for the elastic yarn finger;

Fig. 6 is a view in elevation of such much of the right side of the machine of Fig. 1 as is necessary to show the controls of the elastic yarn finger and some of the needle cams;

Fig. 7 is an enlarged diagrammatic plan view of a portion of the needle circle showing how the sinkers function to measure off the elastic yarn;

Fig. 8 is a developed view in elevation showing the needle yarn drafting operation corresponding to the sinker yarn drafting operation of Fig. 7;

Fig. 9 is an enlarged diagrammatic plan view of another portion of the needle circle showing how the elastic yarn is interlaced and how special sinkers slacken certain wales of inelastic yarn;

Fig. 10 is a developed view in elevation corresponding to Fig. 9 showing the interlacing of the yarns at the knocking over point; while

Figs. 11, 12 and 13 are views in elevation of the main drum cams actuating the thrust rods which control the elastic yarn finger and the needle selecting cams therefor, the parts being shown in their positions for the insertion of the elastic yarn; Fig. 11 showing the thrust rod for

the three needle selecting cams on the right side of the machine shown in Fig. 4; Fig. 12 showing the thrust rod for controlling the special slackening sinker cam shown in Fig. 9; and Fig. 13 showing the thrust rod on the right side of the machine for controlling the elastic yarn finger, the needle draw down cam on the right side of the machine and the elastic yarn sinker-measuring cam of Fig. 7.

In order to incorporate an elastic yarn into plain fabric, as distinguished from rib fabric, it has been necessary heretofore in modern circular knitting machines to provide elaborate mechanism to obtain the vertical separation of needles used to tie in the elastic yarn. This mechanism customarily takes the form of jacks or other selecting elements underneath the needles. According to the present invention it is not necessary to provide such jacks, and the needles are manipulated in a special manner which cooperates with a novel yarn finger in a manner which presents the elastic yarn to the needles in a peculiarly efficient way.

The cams for causing the special manipulations of the needles will be described first. As can be seen by reference to Fig. 1, the machine has the usual leading stitch cam 361 and left-hand stitch cam 360 together with the upper center cam 357, lower center cam 356 and end or side cams 352, 253 and switch cam 415 of the usual revolving needle cylinder circular knitting machine made by Scott and Williams such, for instance, as shown in the patent to Robert W. Scott 1,152,850, dated September 7, 1915. For the sake of clarity the usual narrowing and widening picks are omitted from the drawings. Fig. 1 of the drawings is taken from the inside of the machine looking outward, so that the cams which are carried on brackets on the bedplate of the machine will move toward the observer when inserted. As shown in Fig. 2, the machine is equipped with needles having four lengths of needle butts. One half the cylinder is equipped with the two shorter lengths n^1 and n^2 , and the other half is equipped with the two longer lengths n^3 and n^4 . For example, one half of the cylinder may be equipped with needles whose butts are either .270 inch in length (n^1) or .300 inch in length (n^2). The other half may be equipped with needles whose butts are either .360 inch in length (n^3) or .390 inch in length (n^4). The shorter lengths are on the heel side of the cylinder and the longer lengths on the instep side.

It has been discovered that the needle separation for laying in the elastic yarn can be created without disturbing the making of heels and toes, by making this special separation in two steps or stages as set forth herein. The manipulation of the needles to get the necessary vertical separa-

tion for laying in of the elastic yarn commences after the preceding knitting wave. There is a special lowering cam 383 adapted, when in operative position, to lower needles with certain length butts until the heads of the needles are below the tops of the sinkers. When inserted to a special operative position by mechanism which will be described later, this cam is adapted to engage the three longest lengths of needle butts, namely, all those .300, .360 and .390 inch in length (Figs. 1 and 2). (The cam does not disturb the needles whose butts are .270 inch in length.) When the butts of these needles n^2 , n^3 and n^4 ride out from under the lowering cam 383, they come opposite a raising cam 384. When inserted to operative position this raising cam 384 is adapted to engage only the needles n^4 with the longest length butts, namely those .390" in length. Thus in two operations the needles n^1 and n^4 with the shortest and longest butts, respectively, have been raised selectively above the others. It will be observed that by using these two cams 383 and 384 in this manner to take needle butt lengths as described, a separation is obtained in which one of the two butt lengths on each semi-circle of the needle cylinder has been raised selectively above the other butt length on that semi-circle. It is the shortest butt .270 on the heel side and the longest butt .390 on the instep side which are raised selectively for the purpose of commencing the laying in of the elastic yarn. The order of the needles in each semi-circle can be varied as desired, but in the drawings we have shown every fourth needle as one which is not raised. The raising cam 384 does not raise the longest butt needles to the height from which they were lowered by lowering cam 383, but the heads of these needles are left a fraction of an inch above the tops of the sinkers. It is desirable that the .270 needles and the .390 needles be at the same level, and therefore there is a short lowering cam 385 mounted approximately above the raising cam 384 which lowers the .270 butted needles to the level of the .390 needles, namely, with about $\frac{1}{4}$ " above the tops of the sinkers.

The mechanism for manipulating the lowering and raising cams 383, 384 and 385 is controlled from the main pattern drum 120. The three cams are all mounted on one slide 386 carried in a bracket 387 on the bedplate B at the left side of the machine (Fig. 3). This slide has only two positions, its forward or operative and its outward or inoperative position. It is moved into operation by a drum cam 456 on the main pattern drum 120 by means of a thrust rod 461 (Fig. 11). When the thrust rod 461 is on the drum cam, the slide and its needle cams are inserted. The upper end of the thrust rod is attached to one arm of a bell crank lever 145 pivoted in a vertical plane at the left side of the latch ring bracket 461 on a shaft 139 carrying another bell crank lever 188 for the elastic yarn finger, as will be described later. The other arm 65 of the needle cam bell crank lever 145 is fastened to a rigid wire 146 which extends forward to a position above the bracket 387 carrying the slide 386. At this point the rigid wire 146 is connected to a camming plate 147 swinging about a screw stud 149 on top of the bracket 387. This camming plate presses against a stud 148 projecting upwardly from the slide. The bell crank lever 145 and the camming plate 147 are so arranged that when the thrust rod 461 rides up on 70 the cam 456 the rigid wire 146 is moved to the

rear with the camming plate 147 pressing against the stud 148, pushing the slide radially inward to its operative position. The exact inward adjustment of the slide and its associated cams 383, 384 and 385 is obtained by means of a set screw 150 on the outer end of the slide taking against the bracket 387 (Fig. 4).

As shown in Fig. 1, there is a drawdown cam 389 adapted to act on the butts of all the needles shortly prior to the clearing of the needles. This cam 389 can be located under the usual switch cam 415 if desired, and acts to lower all the needles with the elastic yarn in their hooks before the needles take the inelastic yarn as shown in Fig. 8. In cooperation with this the sinkers may be given a special manipulation, as will be set forth later. The movement of this drawdown cam 389 into and out of operative position is controlled from the main pattern drum by means of a thrust rod 460 (shown in Fig. 13) and its drum cams 457, 458. The drawdown cam itself is carried on a slide 185 mounted on a bracket 391 on the bedplate B on the right side of the machine and is pushed into operative position by a camming plate 186 pivotally mounted on top of the bracket 391 and pressing against a stud on the slide 185 in a manner similar to the pin or stud 148 and camming plate 147 for the slide 386 on the left side of the machine (Fig. 3). The cam 389 can be adjusted vertically by means of the screws which fasten it to the slide, thus varying the draw of the needles at this point (Fig. 6). The connection between the camming plate 186 and the thrust rod 460 consists of a rigid wire 187 connected to the camming plate and to one arm of a bell crank lever 188 mounted in a vertical plane on the opposite end of the horizontal shaft 139 from the first bell crank lever 145. The connection between the wire 187 and bell crank lever 188 is one which yields in one direction and consists of a stud projecting laterally from the arm of the bell crank lever and the wire 187 passing through the stud, and there being a screw collar 195 on the outer end of the wire. The other end of the bell crank lever is pivoted on the thrust rod 460 near the upper end. These parts are so arranged that when the thrust rod is raised the bell crank lever, pushing against the collar 195, pulls rearwardly on the wire 187 and causes the cam 389 to be inserted. On the main pattern drum 120 under the lower end of the thrust rod 460 there is a cam at only one portion of the circumference. This consists of a low cam surface 458 and a high cam surface 457. When the thrust rod 460 is on the low cam surface 458, the bell crank lever 188 will have forced the drawdown cam 389 inwardly until it is in position to engage the two longest lengths of needle butts, namely, those of needles n^3 and n^4 . When the thrust rod is 60 on the high cam surface 457, the drawdown cam will be all the way in, engaging all four kinds of needles n^1 , n^2 , n^3 , n^4 . When the thrust rod 460 drops off the high cam surface 457, the lower arm of the bell crank lever 188 merely slides 65 along the wire 187 without moving that wire forward, and therefore other means are provided to push the drawdown cam 389 radially out of contact with the needle butts when permitted by the thrust rod 460. These means consist merely of a coiled compression spring 196 mounted in the bracket 391 and pressing radially outward against the outer tail of the slide 185. It might be noted at this point that the thrust rod 460 also has control functions with regard to the elastic yarn 70

finger and certain sinker manipulations which will be described later.

The elastic yarn is fed to the needles from a pivoted yarn finger 126 mounted on a bracket 127 on the front of the usual latch ring 550. The finger has a feeding tube 128 whose lower end is held in the finger 126 by a set screw which lower end is just above the top of the highest (i. e., the selected) needles n^1, n^4 . The operative position of the feeding end of the finger is radially just outside the needle circle and its inoperative position is when the finger is pivoted to move the feeding end radially inside the needle circle. The pivotal movements of the yarn finger into and out of operative position are obtained from the high speed gear 65 at the right side of the machine. This gear 65 turns once for every four revolutions of the needle cylinder and there is a cam 591 mounted on the side of the gear. This cam is read by a finger 592 which, when it rides up on the cam, holds the yarn finger out of operative position, i. e., with its feeding end 128 radially inside the needle circle. Normally this finger is pulled radially outward by a spring. We will first describe the connection between the high speed gear and the finger. Attached to the finger below its pivot point is a wire leading to the rear of the machine and fastened to a crank 130 which is pivoted coaxial with the pivot point 552 of the latch ring bracket. Midway on the wire 129 is a screw stud 132 and there is a tension spring 133 between this stud and the bracket 127 of the yarn finger. The end of the wire 129 passes through the free end of the crank 130 with a screw stud 135 to the rear of the crank. With this arrangement it will be noted that the movement of the feeding end 128 of the yarn finger 126 from outside the needle circle to its inoperative position radially inside the needle circle is caused by a rearward swinging movement of the crank 130 pulling the wire toward the rear; while movement of the yarn finger to its operative position is obtained by means of the tension spring 133 whenever permitted by the crank arm 130. Through the pivot point 552 of the latch ring bracket extends a shaft 136 on which the crank arm 130 is mounted, this crank arm being on the left side of the latch ring bracket. At the right side of the latch ring bracket on this shaft 136 there is a depending rod 137 whose lower end engages one arm of a bell crank lever 138 swinging in a horizontal plane about the stud 139 on the end of the latch ring bracket 401. The other arm of this bell crank lever 138 is attached to a rigid wire 140 extending to a position above the high speed gear 65 where it is connected to an arm 141 mounted on the upper end of a vertical shaft 142 pivotally mounted on the table of the machine and on whose lower end is mounted the finger 592. The cam 591 on the gear 65 extends around three-quarters of the outer face of the high speed gear 65 and when the finger 592 is on that cam the bell crank lever 138 is pulled by the rigid wire 140 which swings the crank arm 130 toward the rear, holding the elastic yarn finger radially inward where it cannot feed yarn to the needles.

The connection which idles this control when making portions of the stocking where elastic yarn insertion is not desired is described as follows. Near the upper end of the thrust rod 460 which controls the drawdown cam 389 is a laterally extending stud 143 which overlies a side arm 144 on the depending rod 137 (Figs. 5 and 6). When the thrust rod is off the high drum cam

457 the stud 143 pushes down on the side arm 144 tipping the depending rod 137 and the crank arm 130 so as to pull the wire 129 rearwardly and hold the elastic yarn finger in its inoperative position. This breaks the contact between the 5 depending rod 137 and crank lever 138 and the finger is idle regardless of gear cam 591 and finger 592.

It is contemplated that this invention may be used in a machine where the elastic yarn is not 10 cut between the stockings or anklets until the same have been knit and come off the machine, i. e., where the machine is making what is termed "string" work. In order to do this it is necessary that the elastic yarn be able to pass down 15 inside the fabric tube of the machine when it is not being fed to the needles, and for this purpose the plate 392 which carries the usual cutter and clamp or similar device is recessed or notched at 393, as shown in Fig. 5 of the drawings, to give plenty of clearance for the elastic 20 yarn to pass down inside the needle cylinder.

As already explained, according to this invention the needles are divided into two vertical banks so that the rubber thread will feed into 25 the hooks of the raised needles. The elastic yarn finger is set just to clear the tops of the needles opposite it, and according to this invention the needles are raised immediately after passing the finger so that when the finger is inserted and 30 the point in the fabric where the elastic was fastened in on a previous course passes the finger, the elastic yarn will cut an arc across the raising angle of the needles and will surely be 35 inserted between the needles (see Fig. 1). With the elements arranged as described, the rubber yarn will not catch until the end of the rubber yarn in the fabric has passed the yarn finger, no matter how far ahead of the proper point the rubber finger is swung into operative position. 40 In this way the yarn withdrawn at a certain needle in the circumference of the machine is again inserted at a closely following needle in any following course where it may be desired to insert the rubber yarn. The level of the needles after 45 they have been raised, just subsequent to passing the yarn finger as described, does not raise the needles above the clearing point, as to raise them any higher would clear their stitches and cause the rubber yarn to be knit in at this auxiliary feed instead of interlacing it through the 50 wales at the regular feed as desired.

This construction with the finger located above the needles has another advantage in that in case of a "press-off" there will be no trouble with 55 latches striking the finger.

For the purpose of raising the needles just after they have passed the yarn finger, in order that the elastic yarn Y^1 may be fed to the selected needles a short raising cam 388 is associated with the slide 386 which carries the cams 383, 384 and 385 for the needle selection. This cam 388 is mounted on the end of a long arm 398 pivoted on the bedplate B and it is normally in its withdrawn or inoperative position by virtue of a tension spring 397 extending between the bracket and an intermediate point on the arm 398. In order that the cam 388 may be pressed into its operative position where it engages the 60 butts of all the needles which are opposite it when the needle selecting cams 383, 384 and 385 go into action, there is a pin 395 lying in the bracket 387 whose inner end engages against the 65 arm 398 carrying the cam 388. The outer end 70 75

of this pin is engaged by a set screw 396 in the depending tail of the slide 386. It therefore follows that when the slide is pushed radially inward this pin 396, pressing against the arm carrying the cam 388, will cause the cam to be pushed radially inward to its operative position. The set screw 396 provides a means of accurately adjusting the operative position of the cam.

We have described so far the manner in which 10 the elastic yarn is fed to the needles and the manner in which the needles are selected for that purpose. The manipulation of the sinkers and the needles for the purposes of measuring off the rubber yarn (as shown in Figs. 7 and 8) and 15 slackening the inelastic yarn 12 in certain wales (as shown in Figs. 9 and 10) form the subject-matter of an application for patent filed by Albert E. Page and Frank R. Page on April 8, 1936 Serial No. 73,376.

20 For the purpose of measuring off the elastic yarn as it is drawn from the cone, not only is the particular needle arrangement of value but also the manipulation of the sinkers and the needles at an auxiliary feeding point at the cam 389, as shown in Figs. 7 and 8, is of particular value. Thus at this auxiliary drawdown cam 389 the needles are pulled down to draw certain lengths of yarn over the sinkers while the sinkers serve to assist in this measuring operation 25 by being partially withdrawn until the yarn lies on their knocking-over ledges and then being pushed in again to their normal position which draws bights of yarn in the throats. The means by which all the sinkers are thus retracted before the elastic yarn is fed to the needles consists of an auxiliary sinker cam 189 in the usual 30 sinker cam cap 300 which contacts the butts of all the sinkers 399, 400 and withdraws them slightly (Fig. 7). The result is that the elastic 35 yarn gets below the nebs onto the knocking-over ledges of the sinkers (Figs. 7 and 8). The return movement to normal position is obtained by means of stationary sinker cam 190. The auxiliary sinker cam 189 to withdraw the sinkers is 40 mounted on a spring steel blade 191 on the upper 45 face of the sinker cam cap. When this spring blade is allowed to spring upwardly to its free position the cam 189 mounted on its lower side will not engage the butts of the sinkers but when 45 it is held down it will engage the butts of all the sinkers and pull them out. The stationary cam 190 then draws bights of the elastic yarn between the raised needles. The control of this cam 189 and the spring blade 191 on which it is 50 mounted is obtained from the same thrust rod 460 which controls the idling of the yarn finger and the movement into and out of operative position of the lowering cam 389. The connection 55 between the spring blade 191 and thrust rod 460 consists of a long arm 192 pivoted midway of its length on the latch ring bracket 401. The forward end of this arm 192 overlies the spring blade 191. The rear end of the arm overlies the upper end of the thrust rod 460 and passing 60 through the rear end of this rigid arm 192 is a set screw 193 permitting vertical adjustment of the cam 189. There is a tension spring 194 from the rear end of the arm 192 to the thrust rod 65 to be sure that contact is maintained between the arm and the thrust rod.

A more defined ribbed appearance is obtained when the sinkers on either side of the tying needles slacken the wales where the elastic passes through. The mechanism for thus pushing in

the high butt sinkers 399 on either side of the needle in back of which the elastic yarn has been laid consists of an adaptation of the mechanism of the Robert W. Scott Patent 1,189,220, dated June 27, 1916, using sinkers having different butt 5 lengths and putting sinkers with butts long enough to be acted on by a special sinker cam 312 only on either side of the needles in back of which the elastic yarn is laid. The timing of the insertion and the control and manipulation of 10 the cam 312 can be the same as in the Scott patent. In other words the extra thrust on these special sinkers to slacken the wales is begun just as the needle approaches the bottom 15 of its movement under the leading stitch cam. The slackening cam 312 is controlled from the main pattern drum 120 by means of drum cams 459, a thrust rod 460^b and a thrust plate 470 (not shown) on the upper end of the thrust rod lying 20 against the outer edge of the sinker cam 312. The sinker cam 312 is pivotally mounted in the sinker cam cap 300. To coordinate the use of 25 this thrust rod 460^b for this purpose with the other uses which are made of it, it may be necessary to equip the entire circumference of the main pattern drum 120 in line with the thrust rod with cams of various heights except for the short portion or surface of the main pattern drum which corresponds to the part travelled over by the thrust rod while elastic yarn is being inserted. At this point the thrust rod will be down resting directly on the surface of the main pattern drum 120 and the thrust plate 470 will be pushing against the sinker cam 312 sufficiently 30 to give the special inward thrust of the desired sinkers (Fig. 9).

The construction of the machine having been described, its operation will now be set forth. Assuming that the machine is knitting from top to toe, so much of its operation as relates to the elastic yarn will be described. The main rack wheel (not shown) is given a rack going out of the toe as usual. On this rack the main pattern drum 120 is turned, causing the thrust rod 461 to ride up on the drum cam 456 (Fig. 11). At this moment the semi-circle of needles corresponding to the toe, i. e., the needles n^3 and n^4 having the two longest butts, are opposite the lowering cam 383, the raising cam 384 and the short lowering cam 385 but have not yet been lowered from their inoperative position. The thrust rod 461 pushes in the slide 386 carrying the three cams into their operative positions at this time. Even after the long butt needles are lowered into action the three cams have no effect on the knitting because the elastic yarn finger 126 is still out of action.

When it is desired to start insertion of the elastic yarn the remaining changes are instituted by a high link on the main pattern chain which lowers the main pawl (not shown) into action for four courses. The cycle of movement of the pawl and the location of the next notch in the main rack wheel are such that the rack wheel 65 starts turning almost immediately after the idler goes into operation, and the forward movement of the pawl and rack wheel lasts for almost two courses. The main pattern drum 120 is racked with the main rack wheel. As soon as the rack 70 starts, the auxiliary needle drawdown cam 389 starts to move in as its thrust rod 460 goes up onto the low drum cam surface 458. When the rack begins, the last of the long butt needles n^3 , n^4 are moving away from the switch cam 75

415 and the cam 389 is put into operative relation with those needles which have just passed it, but not far enough in, as yet, to contact the shorter butt needles n^1 , n^2 . Toward the end of the rack the thrust rod 460 rides up onto the high drum cam surface 457 and the drawdown cam 389 goes in the rest of the way where it can contact all needle butts. It makes this second part of its movement while the longer butt needles are opposite it. This drawdown cam assists in measuring off the elastic yarn whenever the same is fed to the needles.

As soon as this rack starts, the main pattern drum releases the elastic yarn finger to its intermittent control by the gear 65 by raising the stud 143 out of contact with the side arm 144 on the depending arm 137. If desired, the cam 591 on the gear 65 may be so positioned that the finger 592 is not on the cam at the moment that the yarn finger 126 is released from the pattern drum control. With such a setting the tension spring 133 at once pulls the feeding end 128 of the finger into operative position. The yarn catches in the hooks of four or five needles and then, having effected this preliminary locating, the cam 591 on the gear 65 engages the finger 592, rocks the depending arm 137 and, pulling on the wire 129, swings the yarn finger 126 out of operation. The yarn goes into the notch 393 in the cutter plate 392 and plays around there for three revolutions of the needle cylinder until the yarn is inserted again. Such a notch is not necessary on some types and sizes of machines.

During the same starting rack the special manipulations of the sinkers are begun. When the thrust rod 460 rides up onto the high drum cam surface 457—which occurs about seven-eighths of a revolution of the cylinder after the rack began—the thrust rod swings the pivoted arm 192, pushing down the spring blade 191 and the auxiliary sinker cam 189 till the latter engages the butts of all the sinkers. The sinkers are thus retracted by the cam 189 and the elastic yarn is laid on the knocking over ledges of the sinkers at about this point (Figs. 7 and 8). The sinkers are then pushed in by cam 190 and simultaneously the needles are pulled down by the auxiliary draw down cam 389, thus causing the elastic yarn to be drawn and measured off by both the needles and sinkers in V-shaped bights between the needles around which the elastic yarn is laid. By laying the elastic yarn around three adjacent needles two such bights of yarn are formed. This insertion of cam 190 begins while the short butt sinkers are opposite the cam.

About one-quarter of a revolution later the slackening of the sinker wales on either side of the needle where the elastic yarn is tied in is commenced. This is caused by the thrust rod 460 riding off the end of the drum cam surface 459 down onto the surface of the pattern drum (Fig. 12). The lowering of this thrust rod causes insertion of the cam 312 (Fig. 9) in the manner shown in the above-mentioned patent 65 to Robert W. Scott No. 1,189,220.

The machine is now adjusted to put in the elastic yarn, the drum cams and their thrust rods being in the positions shown in Figs. 11, 12 and 13. The needle cams are in the positions shown in Figs. 1 and 2, with cams 385, 388 and 389 in position to engage all needle butts, cam 383 to engage the three longest butt needles n^2 , n^3 and n^4 , while cam 384 is adapted to engage only the longest butt needles n^4 . The cams 383, 76 384 and 385 select the groups of three needles n^1

from the heel side of the needle circle and the groups of three needles n^4 from the instep side of the needle circle, and leave them raised above the needles n^2 and n^3 respectively. On a course where the elastic yarn finger 126 is in its operative position, when the last needle which received the elastic yarn the last time it was tied in, passes beneath the lower end of the feeding tube 128 and moves beyond, the yarn assumes a direction which brings it under the hook of about the sixth needle beyond the finger,—the needles n^1 , n^4 having begun their ascent on cam 388 just below the tube 128,—and the elastic yarn is taken by approximately the same needle as the one where it went out. This occurs even if the finger is inserted well in advance of the arrival of the last needle to which the elastic yarn is tied. The needles n^1 , n^4 then ride down cam 389, causing the elastic yarn to go in back of the single needles n^2 , n^3 . At about the same time occurs the pulling of the elastic yarn off the cone by the sinkers and the needles under the influence of cams 190 and 389 respectively, as shown in Figs. 7 and 8. A sharp V of yarn is drawn between every two adjacent needles around which the yarn is laid. This shows the advantage of laying the yarn around a plurality of needles.

However, the needles were not cleared before reaching cam 389, so no stitches are drawn, and as all the needles rise up cam 361 to clear and go through the regular knitting wave, the sinkers are withdrawn, as usual. The needles receive the regular inelastic yarn 12 as usual from the yarn finger F (Fig. 9) and stitches are drawn. The slackening cam 312 then pushes in further than usual the high butt sinkers 399, which are on either side of the needles in back of which the elastic yarn was laid, thus giving the elastic yarn plenty of room to pass through the fabric even when the yarn is contracted, and the stitches are knocked over. When the course of elastic yarn is laid in, the cam 591 engages the finger 592 and the yarn finger 126 is moved inside the needle circle for three courses while the elastic yarn moves around as a chord inside the circle.

When it is time to take the elastic yarn out of action for the balance of the sock or anklet, there is another link on the main pattern chain which actuates the main rack wheel. At the moment that this rack starts, the elastic yarn finger 126 may be out of action because the finger 592 is on the gear cam 591. At the start of the rack the thrust rods 460 and 461 drop off their cam surfaces 457 and 456 to the surface of the main pattern drum. The first part of the downward movement of the thrust rod 460 brings the stud 143 into contact with the arm 144 and the yarn finger is then held out of action regardless of the cam 591 and finger 592. Just a fraction of a revolution before this thrust rod dropped off its cam surface 457 the thrust rod 461 released the slide 386 and the cams 383, 384, 385 and 388 retired under the influence of their springs 397 and 394. The last part of the drop of thrust rod 460 released the spring blade 191 which raised its sinker cam out of action. At this moment the thrust rod 460 rides up on a drum cam, allowing the slackening cam 312 to retire. Thus by the end of the rack all the special adjustments due to the elastic yarn have been eliminated.

What we claim is:

1. In a circular knitting machine, a circle of independent needles and a yarn finger adapted to move across the needle line to present and withdraw a yarn, in combination with cams

adapted to cause all needles to pass below the finger and to cause needles to be raised immediately thereafter till their hook ends are above the feeding end of the yarn finger, whereby the 5 yarn will be inserted at substantially the needle where last withdrawn on a previous course.

2. In a circular knitting machine, a circle of independent needles and a yarn finger adapted to present to the needles at certain courses, a 10 yarn withdrawn at a previous course, and means adapted to lower all needles to pass said yarn finger below the level thereof, in combination with other cam means adapted to raise needles till their hook ends are above the feeding end of 15 the yarn finger at a point immediately following same, whereby the yarn will be inserted at substantially the needle where withdrawn.

3. In a method of operating a circular knitting machine, the steps of withdrawing a yarn finger 20 from feeding position without cutting the yarn and then on a subsequent course reintroducing the yarn at substantially the needle where withdrawn by lowering the needles till they pass just below the level of the yarn finger, moving the 25 finger to operative position outside the needle circle and raising the needles till their hook ends are above the feeding end of the yarn finger just after they pass the finger so as to cause the yarn to begin feeding after the needle where the yarn 30 was withdrawn has been raised.

4. In a circular knitting machine, a circle of independent needles and a yarn finger adapted to move across the needle line to present and withdraw a yarn, in combination with cams 35 adapted to cause all needles to pass below the finger and to cause needles to be raised immediately thereafter till their hook ends are above the feeding end of the yarn finger but not to clear them, whereby the yarn will be inserted 40 at substantially the needle where last withdrawn on a previous course, clearing the needles and feeding and knitting in another yarn on the same course.

5. In a circular knitting machine, a circle of independent needles and a yarn finger adapted to move across the needle circle to present a 45 yarn at certain courses, in combination with means adapted to lower all needles to pass below said yarn finger and to raise selected needles till their hook ends are above the feeding end 50 of the yarn finger immediately after passage by said finger but without clearing same, whereby when the yarn is in its feeding position it will be inserted at substantially the needle where last withdrawn, a second yarn finger adapted to feed yarn to all the needles, and clearing and knitting cams adapted to act on all needles subsequently on the same course.

6. In a circular knitting machine, a circle of independent needles having needles with butts of at least four different lengths, in combination with a yarn finger adapted to present and withdraw a yarn, and cam means adapted to 60 lower all the needles below the level of the yarn finger as they pass it, and immediately thereafter to raise the needles with the outside butt lengths till their hook ends are above the feeding end of the yarn finger whereby the yarn will be 65 inserted at substantially the needle where last withdrawn.

7. In a circular knitting machine, a circle of independent needles having at least four butt lengths, and a yarn finger adapted to present and withdraw a yarn, in combination with cam means adapted to locate two butt lengths at 5 one level and the other two at another level, at the point opposite the yarn finger, both levels being below said finger, and other cam means adapted to raise the needles at one level immediately after passing the yarn finger, whereby the 10 yarn will be inserted at substantially the needle where last withdrawn.

8. In a circular knitting machine, a circle of independent needles having at least four butt lengths, and a yarn finger adapted to present 15 and withdraw a yarn, in combination with a cam adapted to lower needles having the three longest butts and another cam adapted to raise only the longest butt needles, whereby the longest and shortest butt needles are selected and 20 left higher than the others, but below the yarn finger as they pass it, and a cam adapted to raise said selected needles immediately after passage by said finger, whereby the yarn will be inserted at substantially the needle where last 25 withdrawn.

9. In a circular knitting machine, a circle of independent needles having at least four butt lengths, and a yarn finger adapted to present and withdraw a yarn, in combination with cam 30 means adapted to lower the shortest butt needles below the level of the finger and all other needles to a still lower level, and a cam adapted to raise the longest butt needles to the level of the shortest butt needles, and another cam adapted 35 to raise the shortest and the longest butt needles till their hook ends are above the feeding end of the yarn finger immediately after passing same but not to clear them, whereby the yarn will be inserted at the needle where withdrawn. 40

10. In a circular knitting machine, a circle of independent needles having at least four butt lengths, and a yarn finger adapted to present and withdraw a yarn, in combination with cam means adapted to lower the shortest butt 45 needles below the level of the finger and all other needles to a still lower level, and a cam adapted to raise the longest butt needles to the level of the shortest butt needles, and another cam adapted to raise the shortest and the longest butt 50 needles till their hook ends are above the feeding end of the yarn finger immediately after passing same but not to clear them, whereby the yarn will be inserted at the needle where withdrawn, and other cam means adapted to 55 clear all needles and knock them over on the same course.

11. In a circular knitting machine, a circle of independent needles and a yarn finger adapted to present to selected needles at certain courses, a 60 yarn withdrawn at a previous course, and means adapted to cause all needles to pass said yarn finger below the level thereof, in combination with other cam means adapted to raise selected needles till their hook ends are above the 65 feeding end of the yarn finger at a point immediately following same, whereby the yarn will be inserted at substantially the needle where withdrawn.

ALBERT E. PAGE.

HARRY SWINGLEHURST, JR.

CERTIFICATE OF CORRECTION.

June 8, 1937.

Patent No. 2,083,394.

ALBERT E. PAGE, ET AL.

It is hereby certified that error appears in the printed specification of the above numbered patent requiring correction as follows: Page 1, first column, line 7, for the words "yarn in the" read yarn in in the; line 36, for "such" read so; and second column, line 30, for the reference numeral "253" read 353; page 6, first column, line 54, claim 5, for "substatially" read substantially; and that the said Letters Patent should be read with these corrections therein that the same may conform to the record of the case in the Patent Office.

Signed and sealed this 27th day of July, A. D. 1937.

Henry Van Arsdale

Acting Commissioner of Patents.
